[57] CLAIM

The ornamental design for a bracelet, as shown and
described.

DESCRIPTION

FIG. 1 is a top plan view of a bracelet showing my new
design;

FIG. 2 is a front elevational view;

FIG. 3 is a side elevational view;

FIG. 4 is a bottom plan view; and,

FIG. 5 is a perspective view.

The rear of the ornamental attachment forms no part of the
claimed design.
